(57) **CLAIM**

The ornamental design for a display screen or portion thereof with overpayment icon, as shown and described.

DESCRIPTION

FIG. 1 is a front view of a display screen or portion thereof with overpayment icon; and,

FIG. 2 is an enlarged view of a display screen or portion thereof with overpayment icon as shown in FIG. 1.

The broken lines illustrate a mobile device, which is the environment of the design, and which forms no part of the claimed design. The remaining broken lines illustrate portions of the display screen, and portions of the graphical user interface, and form no part of the claimed design.

1 Claim, 2 Drawing Sheets
